UNITED STATES PATENT OFFICE.

ROBERT B. COLLIER, OF COLUMBUS, OHIO.

SECTIONAL FLY-WHEEL.

SPECIFICATION forming part of Letters Patent No. 402,564, dated May 7, 1889.

Application filed June 21, 1888. Serial No. 277,769. (No model.)

To all whom it may concern:

Be it known that I, ROBERT B. COLLIER, of Columbus, Franklin county, State of Ohio, have invented a new and useful Improved 5 Sectional Fly-Wheel, of which the following is a true and exact description, reference being had to the accompanying drawings, which form a part of this specification.

My invention relates to the construction of 10 fly-wheels, and has for its object the construction of fly-wheels in two or more sections by means of devices which will, while enabling the ordinary advantages of sectional construction to be obtained—to wit, stronger and better 15 castings and greater ease in transportation—in addition possess greater strength and rigidity, be more perfectly true than ordinary sectional fly-wheels, and enable liners and shimming to be dispensed with.

Reference being now had to the drawings which illustrate my invention, Figure 1 is a side elevation of my improved fly-wheel made in two sections, and Fig. 2 a central cross-section thereof.

20 A A' indicate the two sections of the wheel proper; B B', the sections of the central web, from which the spokes of the wheel radiate, and which of course are sectioned the same way as the rest of the wheel. C is the hub 25 proper of the wheel, made up, as shown, of a broad annular flange, C', and a sleeve, C².

D is an annular plate of dimensions corresponding to the flange C' of hub C.

E, &c., are bolts provided with heads and 35 nuts in the usual way.

F F are lugs perforated to receive a bolt, f, said lugs being formed, as shown, on the edges of adjoining sections of the wheel-rim.

G indicates a wrought-iron ring shrunk into 40 a recess formed in the casting between adjoining sections of the rim, and G' G' chipping-strips. Both of these devices, being usual in sectional fly-wheels, need not be particularly described.

45 H is the crank-pin.
My fly-wheel is constructed and put together as follows: Two sections, A A', are cast in the usual manner, the abutting ends of the castings being carefully planed and faced off 50 both at the rim and at the central web, B B', so as to fit smoothly and truly against each other. The sides of the central sectional web,

B B', are also to be faced off, so as to be perfectly true, and the central hole therein carefully bored out to fit upon the sleeve C² of the 55 hub C. The annular flange C' of the hub C is faced off, so as to fit truly against one side of the sectional web B B', and the annular plate D is similarly faced to fit against the other side of the sectional web B B'. A large 60 number of bolt-holes are drilled through the flange C', sectional web B B', and the annular plate D, and carefully reamed to give a true and even bearing through all the three pieces for the bolts E, which should be turned 65 to fit neatly in the hole. A perforation should also be formed to receive the crank-pin H, as shown in the drawings, the perforation passing through the flange C', the plate D, and one section of the sectional web B B', and being 70 carefully reamed to fit the turn-pin H. The usual arrangement, such as indicated at F F, f, G, and G', may be used to secure the abutting edges of the rim together.

A wheel made in the above-described manner will be perfectly true and when put together as rigid as though made of a single casting. The sectional castings are stronger and more free from injurious strains than a single casting would be, and the wheel of 80 course much more easily handled, as it can be loaded on the cars in sections and accurately and securely put together at the point where it is to be erected. It will be found desirable to shrink the hub C upon the shaft before 85 shipment. This can be easily done without interfering with the convenience of transportation, as would be the case where the whole wheel was secured to the shaft before shipment.

I have described and shown my improved fly-wheel as made in two sections. Three or even more sections could obviously be constructed in the same manner, and my invention would not be departed from by such a 95 change. The number of sections into which the wheel would be divided is simply a matter of convenience in view of its size.

It is obvious that my invention is applicable not only to fly-wheels, but also to the 100 construction of unusually large gear-wheels, as to which the same advantages would be gained by following my plan of construction.

Having now described my invention, what I

claim as new, and desire to secure by Letters Patent, is—

1. A sectional fly-wheel consisting of a plurality of cast sections, A A', each comprising a portion of the rim and a corresponding portion of a sectional central web, B B', the abutting edges of said sections being carefully faced off to fit against each other, and the sides of the sectional central web being carefully and truly faced, a slotted hub, C, made of a single flanging or casting, and having an annular flange, C', faced off to fit truly on one side of the sectional central web, B B', and having a sleeve, C², turned to fit the central hole in B B'; an annular plate, D, turned and faced to fit on the sleeve C² and against the sectional central web, B B', a number of bolts, E E, arranged to fit in carefully-reamed perforations symmetrically arranged about the hub C and passing through the flange C', the sectional central web, B B', and the plate D.

2. A sectional fly-wheel consisting of a plu-

rality of cast sections, A A', having a sectional central web, B B', the abutting edges of said sections being carefully faced off to fit against each other, and the sides of the sectional central web being carefully and truly faced, a hub, C, having an annular flange, C', faced off to fit truly on one side of the sectional central web, B B', and having a sleeve, C², turned to fit the central hole in B B'; an annular plate, D, turned and faced to fit on the sleeve C² and against the sectional central web, B B', a number of bolts, E E, arranged to fit in carefully-reamed perforations symmetrically arranged about the hub C and passing through the flange C', the sectional central web, B B', and the plate D, all substantially as described.

ROBERT B. COLLIER.
